COMBINED CONTAINER AND STAMP MOISTENER OR THE LIKE

Raymond J. Pajek, 28 Glendale Road, Brockport, N.Y.

Filed Apr. 11, 1960, Ser. No. 60,132

Term of patent 14 years

(Cl. D74—10)

FIG. 1

FIG. 2

FIG. 3

FIG. 4

FIG. 1 is an exploded perspective view of a combined container and stamp moistener or the like, showing my new design;

FIG. 2 is a side elevational view of the same, in closed position;

FIG. 3 is a cross section taken centrally through the lid portion of FIG. 2 showing the depth of the well and the moistening sponges; and

FIG. 4 is a view similar to FIG. 3 with the well cover in the inverted or operational position.

The new design comprises a transparent box having a flat topped wellled recess centered in the outer face of the box cover. The sides of the cover are curved away from the well to the side walls of the container. A moistening sponge is affixed to the undersurface of the well cover, and a matching reservoir sponge is placed in the well, all as shown.

I claim:

The ornamental design for a combined container and stamp moistener or the like, substantially as shown and described.
